[57] CLAIM

The ornamental design for a hosel for a golf club head, as shown and described.

DESCRIPTION

FIG. 1 is a perspective view of a hosel for a golf club head showing my new design with a broken line showing of a golf club head for illustrative purposes only.

FIG. 2 is a side elevation view thereof;

FIG. 3 is a front elevational view thereof;

FIG. 4 is a rear elevational view thereof;

FIG. 5 is a side elevational view taken from the opposite side of FIG. 2;

FIG. 6 is a top plan view thereof.

FIG. 7 is a bottom view thereof.

FIG. 8 is a perspective view of an alternate embodiment of the hosel for a golf club head of FIG. 1.

FIG. 9 is another alternate embodiment of the hosel for a golf club head of FIG. 1.

FIG. 1

FIG. 2

FIG. 3

FIG. 4

FIG. 5

FIG. 6

FIG. 7

FIG. 8

FIG. 9
